United States Patent Office

Des. 188,777
Patented Sept. 6, 1960

188,777

BOAT

Charles A. Matthey, 3231 Madison Ave.,
San Diego, Calif.

Filed Dec. 28, 1959, Ser. No. 58,831

Term of patent 14 years

(Cl. D71—1)

The dominant features of my boat design are shown in full lines.

I claim:

The ornamental design for a boat, substantially as shown and described.
